[57] CLAIM

The ornamental design for a self supported glider swing, as shown and described.

DESCRIPTION

FIG. 1 is a front elevational view of the first embodiment of my new design for a self supported glider swing;

FIG. 2 is a front elevational view of the second embodiment thereof;

FIG. 3 is a top plan view of the first embodiment thereof;

FIG. 4 is a top plan view of the second embodiment thereof;

FIG. 5 is a left end elevational view of both the first and second embodiments thereof, the right end elevational views of the two embodiments being mirror images;

FIG. 6 is a front and left end perspective view of the second embodiment thereof;

FIG. 7 is a rear elevational view of the second embodiment thereof; and,

FIG. 8 is a bottom plan view of the second embodiment thereof.

FIG. 1

FIG. 2

FIG. 3
